UNITED STATES PATENT OFFICE.

HENRY P. HOWE, OF HOLYOKE, MASSACHUSETTS.

PAPER MACHINERY.

1,162,486.

Specification of Letters Patent. Patented Nov. 30, 1915.

Application filed March 29, 1915. Serial No. 17,787.

To all whom it may concern:

Be it known that I, HENRY P. HOWE, a citizen of the United States of America, and resident of Holyoke, in the county of Hampden and State of Massachusetts, have invented certain new and useful Improvements in Paper Machinery, of which the following is a full, clear, and exact description.

This invention relates to paper machinery 10 to be especially employed in conjunction with a machine, or a portion of a Fourdrinier paper machine which in the forward feeding of the continuous web cuts the web into sheets and forwardly delivers the latter to form a pile,—the machine or adjunct 15 constituting the present invention having for its purpose not only to effect the piling of the sheets advanced from the cutter, heretofore in many cases performed by a layboy, but also to conveniently effect a transferring of the pile, after the same has been 20 sufficiently built up, to a further advanced position, leaving the place on the support at which the paper had been piled free or 25 vacant for the taking on of another pile.

Other objects are attained by the present invention which, with the advantages thereof, will be hereinafter rendered apparent.

The invention is described in conjunction 30 with the accompanying drawings and is defined in the claims.

In the drawings:—Figure 1 is a plan view of the forward portion of a sheet cutting machine (or supplement of a paper making or 35 other machine), which comprises the sheet advancing and delivery feed tapes, and of the improved piling and pile transferring mechanism. Fig. 2 is a side elevation of the same. Fig. 3 is a partial sectional view 40 as taken on line 3—3, Fig. 1, on a somewhat larger scale for clearer illustration of the parts, and the relations of the parts, shown therein.

In the drawings, A represents the forward 45 part of a machine of common, well known, and extensively used, character for cutting the continuous web coming to and through the same transversely into sheets. Included in this machine are roll supported and 50 driven feed tapes *a* and *b*, the upper course of the one *b* having running engagements around the foremost roll *d* therefor which is positioned in proximity to and supported by the transverse gage bar *B* included in the 55 present novel mechanism.

Describing the novel mechanism, C repre-

sents a suitable low frame having horizontal rotatable shafts *f*, *f*² at the rear and forward portions thereof, each shaft having opposed pairs *g* and *g*² of toothed wheels affixed 60 thereon.

D represents an endless support or conveyer consisting of transverse articulated flat slats, each having in conjunction with its jointing pivot *e*, and inward projection *h*, 65 these severally and successively having engagements with and between the teeth of the sprocket-like wheels *g* and *g*² for acquiring a chain feed action for the slatted conveyer and support which is of a flexible character as apparent. The edge portions of the support and conveyer D,—at the upper course thereof, are sustained on ledges *i* longitudinally ranging at opposite sides of the frame, whereby such upper course is prevented from sagging, and remains flat and 70 horizontal.

One of the shafts *f*² carrying the toothed wheels *g*², *g*² has means for manually rotating it, such, for instance, as the crank handle *f*³.

E represents a longitudinally ranging gage board supported by brackets *E*², *E*², and extending above a rear end portion of the upper course of the jointed slat conveyer 85 and coincident with, or adjacent to, the rear longitudinal edge of the latter.

The aforementioned transverse gage board B has its location above the rear end portion of the conveyer and it is vertically adjustably movable in conjunction with the aforementioned feed tape roll *d* and has means for effecting its rising and lowering movements which will be now described.

On the upright frame extensions *C*² at 95 the rear, and upstanding above, the frame proper C are a pair of horizontal transverse shafts *G* and *G*² having sprocket chains *H* *H* running around the sprocket wheels *J* and *J*² which are affixed on, and near the opposite 100 ends of, the respective shafts *G* and *G*². The forwardly located vertical courses of these sprocket chains *H* *H* have connections with brackets *k* *k* which are secured to and project rearwardly beyond the transverse 105 gage board B. These brackets have intermediate portions thereof formed as axially vertical tubes *k*² to adapt them to sliding and guiding engagements with the vertical rods *m* suitably supported by and affixed on 110 the frame extensions *C*².

Any suitable means are provided for rotat-

ing the sets of aforementioned shafts and sprocket wheels for effecting the elevation of the gage board and the lowering thereof as from time to time is required in making 5 use of my improved mechanism. In the present instance an intermediate shaft L is provided parallel with the shafts G and G². On this shaft L is affixed a sprocket wheel o, shown as outside of the frame extension and 10 above which, on a suitably extended portion of the upper shaft G is a similar sprocket wheel p around which runs a somewhat shorter endless sprocket chain q. The shaft L has the comparatively large hand wheel L² thereon by means of which through the connections described the transverse gage bar 15 or board B is operated.

The aforementioned brackets k k carried as rearward extensions of the gage board B 20 form supports for the horizontal shaft t which is affixed therein and on which the aforementioned forward tape roll d continuous for its entire length, or divided into a series of short spools, is mounted.

25 The aforementioned gage board B also forms the primary support for the yieldable rollers v v which are above and coact with the advanced portions of the feed tape, which round the roll d for preventing the 30 paper, forwardly moving over and across the gage board, from being upwardly deflected in any undue extent. As specifically shown, these rollers v are carried on the free ends of arms v² which are hung for rocking movements on a cross rod or shaft v³ sustained by fixed arms or brackets v⁴ forming rigid extensions of the cross rod t before mentioned as supported on the gage board provided brackets k.

40 The sprocket chain q and sprocket wheels p and o are duplicated at the rear of the machine, the sprocket chain q² there shown having a counterbalancing weight w thereon, for preventing when not desired, the lowering of the vertically adjusted gage board and 45 for insuring on the turning of the hand wheel L² the easy elevation, more or less as desired, of the gage board.

In the operation and utilization of the 50 improved mechanism described, the sheets cut from the continuous web are advanced by the feed tapes over and forwardly beyond the gage board B and onto the normally stationary support constituted by the upper course of the conveyer D. The attendant 55 squares the sheets with their rear ends edge-wise against the transverse gage board and with their rear sides edgewise along the back longitudinal gage board E. As the pile 60 grows in height, the gage board B is elevated through the turning of the hand wheel L²,— the roll-rounding forward portions of the tapes b, the tape roll d and the yieldable rollers v being bodily carried thereby and 65 movable in unison therewith so that the rela-

tions of the tapes and rolls to the gage board are invariable. After the pile or stack of sheets has become quite high, the gage board E having, from time to time, been elevated step by step, the conveyer is operated manually by turning the crank handle at the forward end of the machine to move the high and heavy pile away from the position on the conveyer at which it had been built up so that the operation of further stacking or 70 pile building against the gages need not be at all interrupted for the removal of the already made pile to a different place.

75 It is a matter of considerable convenience and saving of time to have one made pile 80 on the forward portion of the support and conveyer D while another pile is being formed on the rear of the conveyer, inasmuch as the person having to count the sheets into ream lots may do so from the 85 transferred pile, the only shifting being of the counted lots from off the pile to the proper place of occupancy therefor.

I claim:—

1. In a machine of the character described, 90 in combination, a frame, horizontal rotatable shafts mounted transversely on said frame at the rear and forward portions of the latter, having toothed wheels thereon, an endless support and conveyer consisting 95 of articulated transverse slats having engagements around said wheels, the upper course of which constitutes a table, means for manually rotating one of the wheel-carrying shafts, a longitudinally ranging gage 100 board on said frame and upstanding above a rear portion of the upper course of the jointed slat conveyer, a gage board movably mounted above and transversely relatively to the rear upper portion of the conveyer, 105 means for imparting an elevating adjustment to the transverse gage-board, and means for feeding sheets over the transverse gage board onto the portion of the conveyer adjacent thereto, comprising endless feed 110 tapes and sets of rollers therefor, the rollers for the advanced portions of the feed tapes being supported by, and bodily movable with, the transverse gage board, and yieldable rollers, above and coacting with said 115 advanced tape-rollers, and bodily supported by and movable relatively to the said gage board.

2. In a machine of the character described, 120 in combination, a frame, horizontal rotatable shafts mounted transversely on said frame at the rear and forward portions of the latter, having toothed wheels thereon, an endless support and conveyer consisting 125 of articulated transverse slats having engagements around said wheels, the upper course of which constitutes a table, means for manually rotating one of the wheel-carrying shafts, a longitudinally ranging gage-board on said frame and upstanding above 130

a rear portion of the upper course of the jointed slat conveyer, a gage-board movably mounted above and transversely relatively to the rear upper portion of the conveyer, 5 having brackets extended therefrom, vertical rods supported by the frame with which said brackets have guiding engagements, a pair of shafts one above, and the other below, the transverse gage-board, having 10 pairs of sprocket wheels thereon, sprocket chains around the sprocket wheels, forwardly located vertical courses of which

have connections with said brackets, means for manually rotating one of said shafts, and means for feeding sheets over the transverse gage-board onto the portion of the said conveyer adjacent thereto. 15

Signed by me at Springfield, Mass., in presence of two subscribing witnesses.

HENRY P. HOWE.
